UNITED STATES PATENT OFFICE.

FRED T. REID, OF HARTFORD, CONNECTICUT, ASSIGNOR TO THE POPE MANUFACTURING COMPANY, OF SAME PLACE AND PORTLAND, MAINE.

TUBE-MAKING APPARATUS.

SPECIFICATION forming part of Letters Patent No. 627,205, dated June 20, 1899.

Application filed April 4, 1899. Serial No. 711,673. (No model.)

To all whom it may concern:

Be it known that I, FRED T. REID, a citizen of the United States, residing in the city and county of Hartford, in the State of Connecticut, have invented certain new and useful Improvements in Tube-Making Apparatus, of which the following is a specification, reference being had to the accompanying drawings, forming a part thereof.

10 This invention relates to apparatus for making tubes from hollow ingots in which the ingot passes to grooved rolls over a mandrel which is of necessity held rigidly against movement toward the rolls from the position 15 which has been determined to be best for it. In such apparatus the ingot which is passed through between the rolls is commonly received upon another mandrel, which is held in line with the mandrel first referred to. 20 It sometimes happens that the mandrel over which the tube is drawn gives way by reason of the breaking of its rod or of the back-stop under the severe strain to which it is subjected and is carried with great force against 25 the second mandrel in line with it, causing the rod of the second mandrel to buckle or break and sometimes resulting in the breaking away of a portion of the back-stop which holds the second mandrel. 30 It is the object of this invention to provide means whereby injury to the second mandrel or its rod or back-stop or other part of machine shall be prevented, notwithstanding the carrying away of the first mandrel in the 35 manner referred to. To this end the rod of the second mandrel is so held in its back-stop as to be capable of yielding in a direction away from the rolls when subjected to unusual pressure, although it is held positively 40 by the same back-stop from movement toward the rolls, it being understood that each mandrel in turn may become alternately the mandrel over which the ingot is drawn and the mandrel which receives the ingot from the 45 rolls.

The invention will be described more fully hereinafter with reference to the accompanying drawings, in which are represented merely as illustrations convenient and practical embodiments of the invention.

In said drawings, Figure 1 is a general view,

partly in side elevation and partly in section, illustrating the application of the invention. Fig. 2 is a front elevation of portions of the rolls shown in Fig. 1. Fig. 3 is a longitudinal central section of the upper portion of the back-stop shown in Fig. 1, with the mandrel and its rod shown in elevation and partly broken out to save space. Fig. 4 is a view similar to Fig. 3, but showing a slightly-different arrangement of the holding devices.

Ordinary grooved rolls are indicated in a conventional manner at A A in Figs. 1 and 2, the support therefor being also indicated in Fig. 1 at B. At a suitable distance from the roll is rigidly fixed a back-stop C, which is adapted to support in operative position the mandrel-rod D, which has at its free end the bulb or mandrel d. During operation a second mandrel d' is supported by its rod D' in line with the first rod and mandrel, the ingot being received upon the one rod and mandrel as it is drawn from the other rod and mandrel. It is necessary that the mandrels, particularly that one over which the ingot is drawn, shall be fixed rigidly and immovably with relation to the rolls during the operation, and it is also necessary to provide means for adjusting the position of the mandrel according to the varying conditions of operation. It will be obvious that the second or receiving mandrel is subject to comparatively little pressure under ordinary conditions of operation. It does not require, therefore, to be held positively from movement in a direction away from the roll. Accordingly I have provided means whereby each mandrel shall be held positively from movement toward the rolls and shall be held yieldingly or in such a manner as to be capable of yielding in a direction away from the rolls when subjected to unusual pressure. The head C' of the back-stop is tubular to receive the mandrel-rod through the same, and the latter may be threaded, as at d², to receive lock-nuts d³ and a washer d⁴ on the side of the back-stop remote from the rolls, so that by the engagement, either direct or indirect, of one of said nuts with the back-stop the mandrel will be held positively from movement toward the rolls, but with capability of adjustment. To further facilitate the adjustment of the mandrel, the rod may be passed through a

sleeve E, which is threaded into the head C' of the back-stop C and is provided with a suitable head e, so that it may be turned readily, and with a lock-nut e'. In this case 5 the nut d³ or the washer d⁴ above referred to bears against the end of the screw-threaded adjustable sleeve E. As a means to hold the mandrel-rod firmly and yet to permit movement of the same in a direction away from 10 the rolls when the receiving-mandrel is subjected to ordinary pressure a splint sleeve or clamping-sleeve F is represented in Fig. 3, having a shoulder f to bear against the side of the back-stop toward rolls and having a 15 clamping-bolt f', by means of which the frictional engagement of the sleeve with the mandrel-rod can be regulated. It will be seen that by such means provision is made for holding the mandrel-rod with sufficient 20 firmness under all ordinary conditions and yet for permitting it to slip through the sleeve without buckling or doing any other damage whenever it is subjected to an excessive thrust. In order to provide for a quick clearance of 25 the mandrel-rod in the clamping-sleeve, the diameter of the former may be reduced slightly from a point in front of the end of the clamping-sleeve, as at d⁵. As another means of accomplishing the same purpose the mandrel- 30 rod D is shown in Fig. 4 as having rigidly secured thereto a sleeve G, while the clamping-sleeve F' has a tapered end, as at f², to conform to a tapered seat c, formed in the bore of the tubular head C' of the back-stop C. 35 The clamping-sleeve is forced home in its seat and made to grip the sleeve G of the mandrel-rod D by the pressure against it of the threaded sleeve E. In this case longitudinal adjustment of the mandrel-rod is effected by 40 the lock-nuts d³.

It will be readily understood that various other embodiments of the invention may be constructed without departing from the spirit thereof.

45 I claim as my invention—

1. The combination with rolls, a mandrel and rod for coöperation with said rolls, a second mandrel and rod on the opposite side of said rolls and in line with the first-named 50 mandrel and rod, and a back-stop, of devices

carried by said back-stop to hold the second-named rod and mandrel positively from movement toward the rolls, and devices to hold said second-named rod from movement away from said rolls with capacity to slip or yield, substantially as shown and described. 55

2. The combination with rolls, a mandrel and a rod for coöperation with said rolls, and a back-stop, of devices carried by said back-stop to hold said rod and mandrel positively 60 from movement toward the rolls, and a clamping-sleeve carried by said back-stop and holding said rod frictionally from movement away from said rolls, substantially as shown and described. 65

3. The combination with rolls, a mandrel and a rod for coöperation with said rolls, and a back-stop, of a nut on said rod and engaging said back-stop to hold said rod positively 70 from movement toward the rolls, and a clamping-sleeve carried by said back-stop and holding said rod frictionally from movement away from said rolls, substantially as shown and described. 75

4. The combination with a mandrel and 75 rod, a second mandrel and rod disposed opposite to and in line with the first-named mandrel and rod and a back-stop, of devices engaging said back-stop to hold the second-named rod positively from movement in one 80 direction and devices engaging said back-stop to hold said second-named rod from movement in the opposite direction with capacity to slip or yield, substantially as shown and described. 85

5. The combination with a mandrel and rod, and a back-stop, of devices engaging said back-stop to hold said rod positively from movement in one direction, and a clamping-sleeve engaging said back-stop and holding 90 said rod frictionally from movement in the opposite direction, substantially as shown and described.

This specification signed and witnessed this 1st day of April, A. D. 1899.

FRED T. REID.
